UNITED STATES PATENT OFFICE

HARVEY HURST, OF SOUTH SAN FRANCISCO, CALIFORNIA

FRUIT PULPING MACHINE

Application filed June 7, 1930. Serial No. 459,787.

My invention relates to improvements in a fruit pulping machine wherein a slideable and rotatable spindle is movable to penetrate one side of a piece of fruit and is provided with a member expandable within the body of the fruit to disintegrate the pulp of the fruit within the rind of the fruit and without displacing said pulp from the rind.

The primary object of my invention is to provide an improved fruit pulping machine.

Another object is to provide an improved machine wherein the pulp of citrus fruits and the like may be disintegrated within the rind of the fruit to liberate the juices and to reduce the fibrous body to pulp without displacing the same from the rind.

A further object is to provide an improved machine to disintegrate the pulp of citrus fruit whereby the juices may be consumed directly from the rind.

Another object is to provide an improved machine of the character described wherein pulping means is inserted through one side of a piece of fruit and operated to disintegrate the pulp without piercing or severing the rind at points other than the point of entry.

A further object is to provide an improved pulping machine which will facilitate the preparation of citrus fruits and the like for consumption.

Another object is to provide an improved machine of the character described which is simple and efficient in construction and operation.

A still further object is to provide an improved machine embodying improved features of construction and arrangement producing a compact, attractive, and efficient mechanism.

I accomplish these and other objects by means of the improved device disclosed in the drawings forming a part of the present application wherein like characters of reference

out the specification and drawings, and in which:

Fig. 1 is a side elevation, partly in vertical section, of my improved fruit pulping machine;

Fig. 2 is a broken side elevation, partly in vertical section of the pulping spindle, the figure being drawn upon a larger scale; and

Fig. 3 is a transverse section taken upon the line 3—3 of Fig. 2 in the direction indicated.

Referring to the drawings, the numeral 1 is used to designate in general a supporting base provided with a fruit receiving cup 2 and a vertically disposed standard 3. A suitable electric motor 4 is mounted at the top of the standard 3, the motor being mounted in axial alignment with the center of the cup 2.

A spindle 5 is mounted in connection with the shaft 6 of the motor 4. In the preferred construction illustrated in the drawings, the spindle 5 is feathered into the shaft 6, said shaft 6 being of hollow form to receive the spindle. The spindle 5 extends axially through the motor 4 and is provided at its upper end with a collar 7 movable to engage the upper end of the shaft 6 or the motor housing to limit the downward movement of the spindle through the motor.

The lower end of the spindle 5 is provided with a piercing point 8. An expandable member 9 is mounted in connection with the lower portion of the spindle, said member 9 preferably consisting of a spring metal loop threaded through a slot 11 formed in the lower end of the spindle 5 immediately above the point 8, and having its sides normally extending upwardly in proximate relation to the sides of the spindle. The spring loop member 9 is so formed that the natural spring tension operates to hold the side portions of the loop firmly against the spindle, said side portions preferably being received within longitudinal grooves 12 formed in the sides of the spindle so that the outer surfaces of the loop will normally rest substantially flush

with the surface of the spindle. The point 8 is preferably attached upon the end of the spindle shank by means of a threaded extension 13 operative to secure the point and the 5 lower end of the loop to the spindle.

A sleeve 14 is slidably mounted upon the spindle 5 adjacent the upper ends of the loop member 9, the ends of said loop member 9 being pivotally connected to the lower 10 end of the sleeve 14 by suitable pivot pins 16. The upper end of the sleeve 14 has an annular groove 17 formed therein to receive a collar 18 rotatably mounted thereon. The lower end of the sleeve 14 is chamfered as at 15 19 to facilitate entry into a piece of fruit, as hereinafter more fully described.

A lever 21 is pivotally mounted as at 22 upon the standard 3. The lever 21 is provided with a bifurcated portion 23 having 20 slots 24 formed therein to engage pins 25 extending outwardly from opposite sides of the collar 18 whereby a pivotal movement of the lever 21 will impart an axial sliding movement to the sleeve 14. A spring 26 is 25 connected at one end to the lever 21 and at the opposite end to the standard 3 to normally move the lever 21 to a raised position as shown in full lines in Fig. 1 of the drawings, the lever being movable downwardly 30 against the tension of the spring 26 to operative positions as indicated in dotted lines in Fig. 1.

In operation, a piece of fruit 27, such as 35 an orange or other citrus fruit, is placed in the receiving cup 2, preferably with the stem end upwardly disposed. The lever 21 is then moved downwardly from the normal position indicated in full lines in Fig. 1 to move the sleeve 14 downwardly, the pressure 40 imposed upon the sleeve being imparted through the side portions of the loop 9 to the spindle 5, thereby moving the spindle downwardly, the spindle being rotated rapidly by the motor 4. As the point 8 is moved 45 against the upper end of the piece of fruit 27, the point bores through the rind and penetrates into the fruit, further movement of the lever causing the spindle to extend substantially diametrically through the fruit to 50 a point adjacent the bottom side of the fruit. The downward movement of the spindle 5 is limited by the collar 7 engaging the upper end of the motor housing so that in the lowermost position the point 8 will be positioned 55 just short of the lower portion of the rind, thereby preventing the point from piercing the rind at the bottom of the piece of fruit.

As the spindle 5 reaches its lowermost position, as indicated in dotted lines in Fig. 1 60 the lever 21 will occupy a position such as indicated in the upper dotted position in said figure. A further downward movement of the lever 21 to a position such as indicated in the lower dotted position in Fig. 1 operates 65 to press the sleeve 14 downwardly along the

spindle. This further downward movement of the sleeve causes the sides of the loop member 9 to be expanded to outwardly bowed positions such as indicated in dotted lines in Figs. 1 and 2, and at the same time the 70 lowered chamfered edge of the sleeve 14 is pressed into the opening formed by the spindle in the upper surface of the piece of fruit.

The spindle 5 and loop 9 are rotated continuously while the motor 4 is in operation. 75 During the initial movement downwardly into the fruit, the spindle forms a straight bore into the pulp of the fruit, the loop 9 remaining seated within the grooves 12. When pressure is applied to expand the loop, 80 the rotation of the loop causes the pulp of the fruit to be torn apart, thereby liberating the juices and reducing the fibrous material to a pulp. As the sides of the loop are gradually extended to their extreme extended position, the entire body of the fruit will be 85 disintegrated and reduced to a juicy pulp within the rind, and without displacing the juice or pulp from the rind.

When the lever 21 is released, the spring 90 26 operates to return it to normal raised position, thereby raising the sleeve and returning the loop 9 and spindle 5 to normal raised position. The piece of fruit is then lifted from the cup and the juice and pulp 95 consumed directly from the rind, either by inserting the ordinary straw or drinking tube into the opening formed by the spindle, or by drinking or sucking the juice and pulp directly from the rind.

While I have illustrated and described only one embodiment of my invention, the preferred construction and arrangement disclosed is subject to modification in numerous ways without departing from the spirit of my invention. I therefore do not wish to be restricted to the specific details of construction illustrated and described, but desire to avail myself of all modifications which may fall within the scope of the appended claims. 100

Having thus described my invention, what I claim as new and desire to secure by Letters Patent is:

1. A fruit pulping machine comprising a supporting standard; a power driven spindle mounted upon the standard; means for moving the spindle axially into a piece of fruit; and a spring loop mounted upon the spindle and normally held in proximate relation to the sides of the spindle, said loop being expandible within the body of the piece of fruit when the spindle is moved to its extreme position therein and being rotated by said spindle to disintegrate the pulp of the fruit. 115

2. A fruit pulping machine comprising a power driven spindle; means for moving the spindle axially into a piece of fruit from one end of said fruit; means for limiting the movement of the spindle to prevent punc- 120

- turing the opposite side of the fruit; an expandible member mounted upon the spindle and normally held in proximate relation to the spindle for movement therewith into the 5 piece of fruit; and means for expanding the expandible member within the body of the fruit, said member being rotatable within the spindle to disintegrate the pulp of the fruit.
- 10 3. A fruit pulping machine comprising a supporting standard; a rotatable spindle mounted upon the standard; a spring loop mounted upon the spindle and normally extending longitudinally in proximate relation 15 to the sides thereof; means for moving the spindle axially to penetrate one side of a piece of fruit and to extend substantially diametrically therethrough to a point adjacent the opposite side thereof; and means 20 for expanding the loop within the body of the fruit, said loop being rotated within the fruit to disintegrate the pulp without displacing said pulp from the rind.
4. A fruit pulping machine comprising a 25 supporting standard; a spindle slidably and rotatably mounted upon the standard; expandible means mounted upon the spindle and normally disposed in proximate relation to the sides of the spindle; means upon 30 the standard for rotating the spindle means for moving the spindle axially to penetrate one side of a piece of fruit and to extend substantially diametrically therethrough to a point adjacent the opposite side thereof, the 35 expandible means being spread within the body of the fruit and rotated therein by the spindle to disintegrate the pulp of the fruit without displacing the same from the rind.
5. A fruit pulping machine comprising a 40 slideable and rotatable spindle; expandible means mounted upon the spindle and normally disposed in proximate relation to the sides of the spindle; means for moving the spindle axially to penetrate one side of a 45 piece of fruit and to extend substantially diametrically through the fruit to a point adjacent the opposite side thereof; means for limiting the sliding movement of the spindle to prevent the spindle from penetrating the 50 opposite side of the rind of the fruit; and means slidably movable along the spindle when moved to its extreme penetrating position to spread the expandible means within the body of the fruit, said means being rotated by the spindle to disintegrate the pulp of the fruit 55 without displacing the same from the rind.
6. A fruit pulping machine comprising a 60 slideable and rotatable spindle; a spring loop mounted upon the spindle and normally disposed in proximate relation to the sides of the spindle; means for moving the spindle axially to penetrate one side of a piece of fruit and to extend substantially diametrically 65 through the fruit to a point adjacent the 70 opposite side thereof; means for limiting the axial movement of the spindle to prevent the spindle from piercing the rind upon the opposite side of the fruit; and a collar slidably mounted upon the spindle and engaged by 75 the spindle actuating means for expanding the spring loop within the fruit when the spindle reaches its extreme penetrating position, said loop being rotated by the spindle to disintegrate the pulp of the fruit without 80 displacing said pulp from the rind.
7. A fruit pulping machine comprising a supporting standard; a motor mounted upon the standard; a spindle mounted upon the shaft of the motor for rotation thereby, said shaft being slidably movable axially relative to the motor; an expandible member mounted upon the spindle and normally disposed in proximate relation to the sides of the spindle; a lever pivotally mounted upon the standard 85 and having connecting means engaging the spindle for moving the spindle axially to penetrate one side of a piece of fruit and to extend substantially diametrically through the fruit to a point adjacent the opposite side 90 thereof, said connecting means engaging the expandible member and moving the same to expanded position within the body of the fruit when the spindle is moved to its extreme penetrating position to disintegrate the 95 pulp of the fruit without displacing the same from the rind.
8. A fruit pulping machine comprising a base provided with a fruit supporting cup and a vertically disposed standard; a motor mounted upon the standard in axial alignment with the cup; a spindle connected to the shaft of the motor for rotation thereby, said spindle being slidably movable axially relative to the motor; means for moving the 100 spindle axially to penetrate one side of a piece of fruit supported in the cup and to extend substantially diametrically therethrough to a point adjacent the opposite side thereof, the movement being limited to prevent said spindle from piercing said opposite side; an expandible loop mounted upon the spindle and normally disposed in proximate relation to the sides of the spindle, said loop being engaged and moved to extended position by the 105 spindle moving means when the spindle is moved to its extreme penetrating position whereby rotation of the expanded member operates to disintegrate the pulp of the fruit 110 without displacing the same from the rind.
9. A fruit pulping machine comprising a base provided with a fruit supporting cup and a vertically disposed standard; a motor mounted upon the standard in axial alignment with the cup; a spindle feathered to the shaft of the motor, and having a pointed end movable to penetrate one side of a piece of fruit supported in the cup; a spring metal loop mounted upon the spindle, said loop passing through the spindle adjacent the 115 120 125 130

pointed end, and the sides of said loop normally being disposed in proximate relation to the sides of the spindle; a sleeve mounted upon the spindle and engaging the loop; a collar rotatably engaging the sleeve; and an actuating lever pivotally mounted upon the standard and engaging the collar to move the spindle axially to penetrate the fruit and to expand the loop within the body of the fruit, rotation of the expanded loop operating to disintegrate the pulp of the fruit without displacing the same from the rind.

In witness whereof, I hereunto set my signature.
